UNITED STATES PATENT OFFICE.

JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

ARTICULATED TRUCK.

1,184,023.

Specification of Letters Patent. Patented May 23, 1916.

Application filed May 23, 1914. Serial No. 840,551.

To all whom it may concern:

Be it known that I, JOHN M. ROHLFING, residing at St. Louis, Missouri, and being a citizen of the United States, have invented 5 certain new and useful Improvements in Articulated Trucks, of which the following is a full, clear, and exact description, such as will enable others skilled in the art to which it appertains to make and to use the 10 same, reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is a plan view of the improved articulated truck. Fig. 2 20 is a side elevation of a twin hopper car body mounted upon the articulated truck. Fig. 3 is a side elevation of the central truck member, partly broken away to show more clearly the action of the equalizers. Fig. 4 25 is a transverse sectional view of the central truck member, taken on line 4—4 of Fig. 1. Fig. 5 is a detail view of one of the roller containers secured to the end of the central truck member. Fig. 6 is an enlarged frag- 30 mentary plan view, illustrating the relationship of the center and end truck members, and details of construction thereof. Fig. 7 is a central longitudinal section of the parts shown in Fig. 6, and is taken on line 7—7 35 of that figure. Fig. 8 is a detail transverse section through one of the bearing plate castings carried by the end truck members. Fig. 9 is a fragmentary plan view, showing one of the forward corners of one of the 40 end truck members. Fig. 10 is a side elevation of the same. Fig. 11 is a detail trans- 45 verse sectional view taken on line 11—11 of Fig. 10. Fig. 12 is a similar view but taken on line 12—12, of Fig. 10. Fig. 13 is a plan view of an associated pair of the pedestals carried by the end truck members. Fig. 14 50 is a plan view of one of the middle pairs of pedestals carried by the central truck mem- 55 bers. Fig. 15 is a front elevation of the same. Fig. 16 is a side elevation of the pedestals shown at the left in Fig. 15; and Fig. 17 is a side elevation of the pedestal shown at the right.

The articulated truck herein disclosed is 55 of substantial and rugged construction, and

is provided with a comparatively large number of wheels and axles, distributed throughout a long wheel base, whereby the truck may easily take any curve, and also equalize the load over a large portion of the track, 60 thus proving less destructive to the latter than where short wheel bases are used.

While in the particular embodiment of the invention here illustrated and described, ten 65 wheels have been employed, this is merely symbolic as any number and combination of wheels and axles may be used, the adaptation depending upon the kind and arrangement of the car body to be superimposed 70 upon the truck.

In an application filed by me contemporaneously with this, and covering a hopper car with articulated truck, I have shown the truck herein set forth, and the application of that type of car furnishes an apt 75 illustration of many of the advantages derived from the use of this type of truck. And particularly with reference to having predeterminedly spaced apart unrestricted 80 discharge openings in the end truck members. Not only is there a conservation of the track rails secured, but there is less wear and tear on wheel flanges, journals and bearings, etc., and less motive power is required to move a given load. The method 85 of equalizing enables the several axles to be independent of each other, resulting in easy running over uneven tracks, while the mode of supporting and guiding a car body by castings containing rollers and guiding 90 slots, and which castings are sustained by the truck, contributes to the smooth moving of the truck and car body as a combination. As it is composed of commercial steel shapes, and a few comparatively small castings, the 95 truck is relatively inexpensive to construct and to keep in repair. And the parts are readily accessible for such repair and inspection.

Severe shocks, ordinarily present and due 100 to the swaying of a car body, are eliminated by the arrangement of the points of support, which prevent oscillation of the car body. This is a highly important feature as it lessens the possibility of derailment.

Referring now to the drawing, the form 105 of the articulated truck shown comprises a central or intermediate truck member A adapted to have lateral movement with respect to a carbody, indicated at D in dot 110

and dash lines in Fig. 1, and in full lines in Fig. 2, and oppositely extending end truck members B and C.

The three truck members A, B and C have a common pivotal connection with each other, and each is capable of movement independent of the remaining truck members, whereby sinuous tracks may be traversed without difficulty.

All of the members of the articulated truck are provided with wheels 17, mounted upon axles 18 which are revoluble in journal boxes 19. The central truck member A, forming a partial support for both end truck members, is preferably supplied with a plurality of wheels and axles, this being in keeping with its strength requirements, and enabling it to bear its proportion of the load and possess great stability. It is sufficient that each end truck member B and C be provided with a single pair of wheels and an axle, preferably at the outer end of each, but this statement is not to be regarded as a limitation. Such single pairs, so arranged, act admirably to guide the forward moving end of the composite truck structure, and to trail the rear end in a non-resistant manner.

The journal boxes 19 are retained between pedestals 20, 21, 22 and 23, are kept in alignment thereby, and are vertically slideable therebetween. Some of pedestals 20 are paired with pedestals 21, and are secured to spaced apart parallel longitudinal members 26 and 27, which may be channels, and are respectively the outer and inner elements of each of the side frames of the central truck members A. Secured also to these longitudinal members 26 and 27 of each truck side frame are other paired pedestals 20 and 23.

Each end truck member B and C comprises at opposite sides thereof side frames of spaced apart longitudinal members 24 and 25 shown as channels, though not limited in this respect, which are respectively, the outer and inner elements of each side frame of these trucks. At the outer ends of each of the side frames of the end truck members B and C, the longitudinal members 24 and 25 are shown as spaced farther apart, this being usually accomplished by a compound lateral bending of channel 25. Within each wider space, and attached to the interior vertical walls of said longitudinal members, are paired pedestals 20 and 22. By proper spacing, the bending of channels 25 may be avoided, if desired, and as a matter of fact, the side frames may vary widely from the form shown.

The pedestals 20 and 22, of the end trucks are connected at the bottom by relatively short tie plates 28, while pedestals 20, 21 and 23 associated with the central truck member side frames, may have their bottom

portions connected by continuous tie plates 29, each spanning the distance between the extreme pedestals of each side frame.

Journal boxes 19 are provided on their top surfaces with teats 19^a, see Fig. 12, which serve as positioning means for spring seats 30 mounted upon said journal boxes. Resting within the seats 30 are springs 31 of suitable capacity, those carried in the seats upon the journal boxes located in the end truck members B and C having spring caps 32, bearing against their tops, said spring caps being fastened to side frame members 24 and 25. Thus each end truck member is supported on its separate pair of wheels.

The central truck, or truck member A of the articulated truck, is formed with spaced side frames, each of which includes a pair of longitudinally extending channel shaped members 26 and 27, properly spaced apart, and the pairs of members 26—27 at opposite sides, are connected by end sills 16 (one at each end), and are also connected by transoms 45.

In the central truck member, spring caps 33 are employed, and are not directly attached to the side frames of this member, but are capable of moving freely in a vertical direction between the longitudinal members 26 and 27 thereof. Upon the spring caps 33, are supported equalizers 34 two of which are positioned between the members 26 and 27 of each of the central truck member side frames.

Each equalizer 34 rests upon the cap plate 33 of a pair of springs 31 supported by one of the journal boxes located toward the end of the central truck member and upon one end of the cap plate 33^a of the pair of springs sustained by the intermediate journal box in the same side frame of the central truck member. There are, therefore, two equalizers 34 between the longitudinal members 26 and 27 of each side frame with their inner ends in proximity to each other.

Suitably suspended from a proper point of each equalizer 34 is a hanger 35, here shown as having an inverted U-shape, and being provided with slots 36, (see Figs. 3 and 4). In these slots are placed pins 37, upon which bear the longitudinal side frame members 26 and 27, resulting in the resilient support of the entire framing of the central truck member upon its several pairs of wheels.

The shape and arrangement of the hanger slots and pins, as clearly shown in Figs. 3 and 4, and the strength of the material of which the pins are constructed, is such that the pins 37 cannot be displaced or lost, except through improbable breakage.

Because of the arrangement of the equalizers and their associated parts, the load is uniformly distributed on all the springs in the central truck frame, and the wheels are

permitted easy running over uneven tracks, the said equalizers acting independently of each with a consequent independence of each pair of wheels resulting.

5 To the longitudinal members 26 and 27 of each side frame and spanning the same, is secured a strong centrally located casting 38, both of which castings are designed to receive the pulling and buffing stresses transmitted to and from the car body by suitable castings attached thereto. Each casting 38 has braced impingement walls and a runway for antifriction devices that are operable by the stress-transmitting castings secured to 15 the car body.

Each casting 38 has a base portion 38^a adapted to be riveted to and connect the truck side-frame members 26 and 27. From this base portion rise transversely extending vertical walls 38^b forming, with the base portion 38^a, sockets for the reception of lugs and rollers F depending from a car body. (see Fig. 2). The walls 38^b are braced by ribs 38^c rising from the base and extending longitudinally of such base portion, hence the draft casting 38 of the center truck is admirably adapted to connect the center truck side-frame members, and also to transmit draft stresses.

30 The central truck member frame, has its side frames connected by transverse end sills or end pieces 16, and intermediate transoms 45, the former being shown as channels and the latter as I-beams, though any suitable construction may be substituted therefor. Transoms 45 are here shown as equidistantly disposed on either side of the central transverse center line of the central truck member, which also passes through the 40 center of the pulling and buffing castings 38.

Connecting transoms 45, and equally disposed either side of the longitudinal median line of the central truck member, are relatively short longitudinal channel, or other 45 shaped, transom tie pieces 46. A convenient way of securing the transoms and transom tie pieces together is through the use of connection angles.

Between the transom tie pieces, and at 50 the intersection of the transverse and longitudinal median lines of the central truck member, is located a center pivot casting 47, securely affixed to and supported by said transom tie pieces 46. The pivot casting 47 has a central vertical hole for the reception 55 of a center pin 7 which may turn freely therein.

Central truck end sills 16, and transoms 45, may be supplied with top and bottom 60 cover plates, and transom tie plates 46 with top cover plates, as shown. It is good practice to stiffen some or all of the cover plates, as with angles, the end sill top cover plate 70 being shown in Fig. 7 as being so reinforced by the angle 71.

The frames of end truck members, B and C, are of like construction, having the hereinbefore mentioned side frame, comprising longitudinal members 24 and 25. The inner ends of said side frames of each end truck 70 member are connected by an end sill in the form of a cross-bearer member 41, shown as an I-beam of less depth than central truck member end sills 16 and suitably joined to the side frames by connection angles or 75 plates. The outer ends of said end truck member side frames are illustrated as being connected end sills in the form of vertical channels 15, which extend a considerable distance below said side frames. Secured to 80 the downward extensions of channels 15 of the side frames of each end truck member, is a transverse end truck member end piece, such as a channel 14, suitably reinforced, if desired, by an angle 13 along its upper edge. 85

The longitudinal members 24 and 25 of the side frames are preferably provided with top and bottom cover plates 11 and 12, which, however, do not extend to the outer ends of said side frames, thereby leaving 90 space for inserting springs.

Each cross-bearer member 41 is provided with a top cover plate 10, which overlaps the top cover plate of one of the central truck member end sills 16, and also extends 95 around over a portion of members 24 and 25 of each of the side frames of the same end truck member.

To the central truck member end sills 16, are strongly attached supporting brackets 100 comprising roller containers 39, preferably in the form of castings, in which containers are rollers 40, upon which the adjacent cross-bearer member 41 rests and is adapted to roll, thus partially supporting each end 105 truck member upon the central truck member.

The end sill 16 of the central truck member is relatively deep and the end sill or cross bearer truck member 41 of the end truck is relatively shallow. The end sill 41 is connected to the side-frame members 24 and 25 by knee braces 41^a, and the lower portions of the members 24-25 are cut away at H to clear the supporting brackets 110 39 and permit the lower edges of said side-frame members of the end truck sections to occupy substantially the same plane as the lower edge of the side-frame members of the central truck section. This for convenient attachment of the journal box pedestals 20 to 23, inclusive.

The inner end of each truck member has a yoke 49 which is secured in the present instance to the cross-bearer member 41 and 125 its top plate 10 by connection angles and extends away therefrom and substantially to the center of the central truck member. These yokes may be constructed of Z-bars and made to converge as they depart from 130

cross-bearer 41 to have V-shaped formation. At the vertex of the V, they are connected by angles 9 having inwardly extending flanges, which angles are bent to conform 5 to the inner face of the webs of their respective Z-bars, by said inwardly extending flanges of each reinforcing angle 9 to a strengthening and swivel plate 8, which extends beyond the Z-bar and is perforated 10 for the passage of pivot pin 7. The latter passes through both swivel plates 8 and through the center pivot casting, and is retained in place by a cotter pin or gib.

The swivel plate 8 attached to the yoke 15 49 of end truck member B, is placed in a lower plane than the swivel plate of end truck member C, that the latter plate may ride upon the former, and, as the bottom flanges of both Z-yokes are in the same 20 plane, a filler plate 6 is inserted between the bottom flange of the yoke of the end truck B and the swivel plate 8 affiliated with that yoke.

The extreme end of the swivel plate carried 25 by the yoke of end truck C is crimped and overlaps the bottom flange of the yoke 49 of end truck member B. Thus a compact, non-interfering and self-position-retaining swiveling construction is devised, 30 when center pin 7 is secured in place.

Resting upon the cover plates 11 and secured to the longitudinal members 24 and 25 of the side frames of each end truck member B and C, is a car body supporting 35 and guiding structure 42, being by preference a casting. Rollers 43 are contained therein upon which a car body rests. When there is a swiveling of an end truck member, there is a relative longitudinal movement 40 between said truck and the car body and the supporting rollers 43 practically eliminate friction therebetween.

An elongated opening 44 is present in each casting 42, and into each projects a 45 depending arm or extension from the car body structure.

When either end truck member swivels, the projections from the car body affiliated with the castings 42 on each side frame of 50 that truck member have relative longitudinal movement with respect to the slots they occupy. That is to say, due to the curvilinear path of travel of the castings 42 carried by the swiveling truck's side frames, 55 one of said castings will move away from the central transverse plane of the truck as a whole, and the other casting will move toward it. Therefore, when said end truck member is aligned with the central truck member, the projections from the car body 60 will occupy the middle portion of the slots in the castings 42, but when these said truck members are angularly disposed to each other, one car body projection will occupy 65 a position nearer one end of its slot, while

the projection from the opposite side of said car body will occupy a position correspondingly nearer the opposite end of the slot in the casting on that side of the end truck member.

There being two end truck members, each having a pair of side frames, there will be four guiding and supporting structures 42 to support and retain the car body in substantially frictionless relation upon the articulated truck, in such manner as to permit whatever lateral movement of said car body is necessitated by track curvatures.

Reverting to the pedestals 20, 21, 22 and 23, their different constructions are provided to permit the proper positioning of the truck springs. The spring seats 30 and springs 31 are lowered between longitudinal side frame members 24 and 25, and pushed into place under spring caps 32, the operations being facilitated by the peculiar shape of pedestals 22.

In the central truck member, the end sets of springs seats 30, springs 31 and movable spring caps 33 may easily be dropped into place between the longitudinal side frame members 26 and 27. But the central spring sets must be lowered between members 26 and 27 and pushed into place, castings 23 being specially shaped to render the accomplishment easy.

Each pedestal 20, 21, 22 and 23 has a main portion principally of U-shaped section, but converted near the top into an I-shaped section. Pedestals 20 and 21 have upstanding arms 50 connected by the web of the I-shaped part of the main portion, said I-shaped part aiding in retaining the springs 31 in place and said arms are detachable to the inner faces of the longitudinal members 105 of the truck side frames with which they are associated.

Each pedestal 23 has a single similar upstanding arm 51, but the web of the I-shaped portion is retained within the main pedestal portion, and does not obstruct springs 31 when they are forced into position and said arm is adapted to be attached to the outer face of one of said longitudinal members.

Pedestal 22 has a horizontal integral 115 trough-shaped spring-guide 52, adapted to span the space between said longitudinal side frame members, and said trough is flanged for connection to them. Springs 31 are directed by guide 52 when being forced 120 into position under spring cap 32.

After all the springs, their seats and caps, are in place, the equalizers 34 are properly positioned upon the movable spring caps and between the side frame longitudinal members and the hanger pins 37 inserted in the hangers depending from the equalizers, completing connections.

The equalizers 34 are preferably constructed of I-beams, the inner end of each 130

of which is slit. The portion above the slit is pressed outwardly and downwardly, and the upper web portion is caused to bear against and lap the web portion below the slit, and both web portions are riveted together. The inner ends of the equalizers are thus reduced in altitude and may pass beneath the draft castings 38, and permit ample clearance between said castings and themselves.

10. What I claim is:

1. An articulated pedestal truck comprising a plurality of end truck members and a central truck member having a common pivotal connection, the central member supporting the adjacent end of the end sections. 15
2. In an articulated pedestal truck, end members capable of connection with and swiveling movement with respect to a car body, and commonly connected with an intermediate truck member capable of movement transversely of said body, a plurality of wheels and axles supporting all of said truck members, each truck member having such a number of wheels and axles as is proportionate to the load it is to sustain. 20
3. In an articulated pedestal truck, substantially co-extensive with a car body, and comprising swiveling end truck members adapted to interlock with a car body and an intermediate truck member adapted to partially support said end truck members and to move transversely of said body, all the truck members having a common pivotal connection, and wheels and axles supporting all said truck members and disposed with regard thereto in proportion to the load-sustaining capacities of each truck member and to give a long wheel base. 25
4. In an articulated truck adapted to support a car body, end truck members connected to and swiveling from a point on an intermediate truck member adapted to move transversely of said body and having side frames and pulling and buffing stress-receiving devices secured to each of said side frames. 30
5. In an articulated truck for supporting a car body, end truck members commonly articulated with an intermediate truck member adapted to move transversely of said body, intermediate truck side frames comprising a pair of spaced longitudinal members, and pulling and buffing stress-receiving castings spanning and secured to each pair of longitudinal members, and each having braced impingement walls and a run-way for anti-friction devices operable by stress transmitters on said body. 35
6. In a railway truck, end truck members, adapted to swivel transversely of a car body and independently of each other, each being articulated with and at the center of swiveling of an intermediate truck member transversely movable of said body, and a
- plurality of end truck member supporting devices carried by said intermediate truck member adapted to partly support said end truck members and to permit substantially frictionless movement between them and said intermediate truck member. 70
7. In a railway truck, end truck members each having side frames and adapted to swivel transversely of a car body and independently of each other, each being articulated with and at the center of swiveling of an intermediate truck member transversely movable of said body, and car body supporting and guiding means comprising a plurality of devices each secured in a uniformly load-distributing position upon each of said end truck side frames, each device being capable of curvilinear movement and comprising a supporting member with a car body-guiding extension, slotted to receive coöperating means from said body, and containing anti-friction means operable by the lateral component of said curvilinear movement of said device and the relative longitudinal movement of said car body. 80
8. In a railway truck, oppositely extending swiveling end truck members, articulated with and at the center of swiveling of an intermediate truck member movable transversely of a car body, pulling and buffing stress-receiving devices on side frames of said intermediate truck member adapted to coöperate with stress transmitters on said body, car body-supporting, guiding and position-retaining means on side frames of each end truck member adapted to be overlapped by said car body and to coöperate with guiding and retaining means on said body. 90
9. In an articulated truck, an intermediate traction-impulse-receiving truck member movable transversely of a car body, oppositely extending swiveling end truck members on opposite sides thereof having a common point of articulation with said intermediate truck member, each end member comprising side frames having spaced apart longitudinal members suitably tied together, a cross-bearer member connecting inner ends of said side frames and having rollable support upon said intermediate truck member, vertically disposed connection pieces joining the outer ends of said longitudinal members in each side frame and extending therebelow, and suitably shaped and reinforced end pieces connecting said connection pieces. 105
10. In a railway truck, swiveling end pedestal truck members, each articulated with and at the center of swiveling of an intermediate truck member transversely movable of a car body, side frames for each truck member spring-supported upon journal boxes slidably mounted in pedestals attached to the respective sides thereof, axles 110
- 120
- 125
- 130

- revoluble in companion boxes and wheels mounted on said axles, each pair of axles connected wheels having independent action.
11. In a railway truck, swiveling end truck members having a common point of articulation with an intermediate truck member adapted to move transversely of a car body, frames for each end truck member directly supported upon springs mounted on a single pair of journal boxes, an axle, carrying wheels, and revoluble in said boxes, a frame for said intermediate truck member having side frames, a plurality of equalizers within each side frame from which the latter is hung and groups of springs resting on different journal boxes and adapted to so support the several equalizers that the axles and wheels revoluble in companion boxes have independent vertical movement.
12. In a railway truck, a truck frame having side frames, the latter each comprising spaced apart longitudinal members, pulling and buffing stress-receiving devices spanning and mounted upon each set of said longitudinal members, and a plurality of equalizers positioned between the latter and passing beneath the stress-receiving devices and being spring-supported upon journal boxes, each equalizer comprising an I-beam slit at one end, with the upper portion depressed and the web part thereof lapping and being secured to the web part of the lower portion.
13. In a railway truck, side frames, each comprising a pair of laterally spaced flanged members, appropriately separated pedestals positioned therebelow, each comprising a main portion principally of U-shaped section but converted near the top into an I-shaped section, a journal-box guideway in said U-shaped portion, upstanding arms each secured to an inner face of one of said members, laterally extending flanges attached to flanges of the latter, the web of said I-shaped portion connecting said upstanding arms, and a pedestal tie bar joining both pedestals.
14. In a railway truck, side frames each comprising a pair of laterally spaced flanged members, a pair of appropriately separated pedestals positioned therebelow, each comprising a main portion principally of U-shaped section but converted near the top into an I-shaped section, a journal box guideway in said U-shaped portion, attachment means for one pedestal comprising a pair of upstanding arms connected by the web of said I-shaped portion and each having an outstanding flange, attachment means for the other pedestal comprising a single upstanding arm and an outstanding flange on said main portion, the former means being attached to inner faces and flanges, and the latter means to an outer face and a flange, of said members, the I-shape portion of the second-mentioned pedestal terminating within said main portion, and a pedestal tie bar connecting both pedestals.
15. In a railway truck, side frames each comprising a pair of laterally spaced flanged members, a pair of appropriately separated pedestals positioned therebelow, one comprising a main portion principally of U-shaped section but converted near the top into an I-shaped section, a journal box guideway in said U-shaped portion, integral upstanding arms connected by the web of said I-shaped portion each secured to an inner face of one of said members, and outstanding flanges attached to the flanges of the latter and the other comprising a main vertical portion principally of U-shaped section but at the top expanded into a horizontally disposed trough-shaped spring guide, spanning said members and flanges for attachment to flanges of the latter, and a journal box guideway in said U-shaped portion, and a pedestal tie bar connecting both pedestals.
16. In a railway truck, side frames each comprising a pair of laterally spaced flanged members, pedestals depending therefrom, journal boxes with spring positioning means slidably mounted therebetween, spring seats co-acting with said positioning means mounted on said boxes, springs in said spring seats, and reinforced spring caps bearing upon said springs and secured to and between said members.
17. In a railway truck, side frames each comprising a pair of laterally spaced longitudinal members supporting a plurality of pairs of pedestals each pair guiding a journal box, springs mounted upon each journal box, movable cap-plates superimposed on the springs of each box, oppositely extending equalizers positioned between said members and commonly supported upon the cap-plate of a central spring set and each supported upon the cap-plate of a spring set located at one side of said central set, inverted U-shaped hangers attached to and supported by and embracing said equalizers, and hanger pins in each hanger supporting said members.
18. In an articulated truck, swiveling end truck members having inwardly extending perforated yokes, and an intermediate truck member, comprising side frames including spaced apart longitudinal members, end pieces and transoms connecting said side frames, spaced apart longitudinal transom tie pieces joining said transoms, a central pivot-holding device located between and secured to said transom tie pieces, and a pivot passing through said yoke perforations and central pivot-holding device.
19. In an articulated truck, end truck members and an intermediate truck mem-

- ber, a perforated centrally located pivot casting secured in the latter, inwardly extending V-shaped yokes of Z-section secured to each end truck member, perforated swivel 5 and strengthening plates secured to the vertex portion of said yokes by connection angles conformed to webs of said yokes, said plateslapping each other, and one being crimped to bear on one of said Z-shaped 10 yokes, a filler plate inserted between the same yoke and its associated swivel plate, and a pivot pin passing through said swivel plates and pivot casting.
20. In an articulated truck, a central section and end sections, all pivotally connected together at a common point, said sections each having side frame members and draft transmitting means on said side frame members adapted to interlock with coöperating 15 eans on a car body.
21. An articulated truck comprising a central section and interconnected end section supported on brackets extending from the central section.
22. In an articulated truck, a central truck section and end truck sections, each of which is provided with a side frame which is adapted to interlock with a car body.
23. In an articulated truck, a central 25 truck member having side frames and end sills, brackets extending from said end sills and end truck members having end sills supported by said brackets.
24. In an articulated truck, a central 30 truck member and end truck members each having pairs of side frame members spaced apart on its opposite sides and castings—adapted to interlock with means on a car body—connecting the members of said pairs 35 of side frame members.
25. In a truck, a side frame comprising spaced members and means connecting said spaced members adapted to have an interlocking engagement with a car body.
26. In an articulated truck, a central section and end sections pivotally connected together and to the central section, each of said sections comprising side frames each of which is formed of spaced members and 40 means connecting said spaced members adapted to have an interlocking engagement with a car body.
27. An articulated truck comprising three 45
- interconnected sections each of which includes spaced and connected side frames, in combination with means connected with each side frame adapted to interlock with a car body.
28. A truck side frame comprising spaced members and a draft casting connecting said 50 members.
29. An articulated pedestal truck comprising a central section and end sections each of which is provided with socketed draft transmitting castings thereupon and the draft transmitting castings of the end sections including friction reducing means.
30. In combination, three pivotally connected truck sections each of which has spaced side frames with draft castings 55 mounted thereon and journal box pedestals lapping and depending from said side frames.
31. In combination, three pivotally connected truck sections each of which has spaced side frames, with draft castings mounted thereon, one of the truck sections being provided with longitudinally extended friction reducing supporting means and each of the other truck sections including an 60 end sill mounted on one of said supporting means.
32. In combination, spring supported equalizers, side frame members supported by said equalizers, draft castings connected 65 to the side frame members, means connecting the side frames on opposite sides of the truck and end truck sections supported on said connecting means.
33. In combination, a center truck section 70 comprising pairs of spaced side frame members, springs supported between the members of each pair, a plural part equalizer supported by said springs, hangers supporting the side frame members from the equalizer bars and draft transmitting members 75 adapted to transmit pulling and buffing stresses from a car body directly to said side frame.
- In witness whereof I have hereunto set 80 my hand in the presence of two witnesses.
- JOHN M. ROHLFING.
- Witnesses:
- JAMES J. COOPER,
ROBERT J. SCHEIBLI.
